INKING MECHANISM FOR PRINTING MACHINES

Clifton Chisholm, Cleveland, Ohio

Application September 15, 1938, Serial No. 230,034

5 Claims. (Cl. 197—158)

This invention relates to an inking mechanism for printing machines, and is more specifically concerned with the type of printing machine wherein there is a member carrying a plurality of printing characters and wherein more of the characters are inked in one cycle of operation than are used to make an impression in one cycle of operation. In such a machine my mechanism operates to remove excess ink which tends to accumulate on the unused characters.

My invention is well adapted for embodiment in a machine having a plurality of type-carrying wheels side by side which may be shifted axially to select a wheel for printing, the whole set being rotated while in coaction with an inking roller to select one desired character for the impression. In such plural embodiment the accumulation of ink is augmented.

The type wheel or wheels and the entire inking mechanism may be mounted in a frame which is moved to make the impressions and in such case I give the fountain roll partial rotations by a stationarily mounted pawl which coacts with a ratchet on the fountain roll to turn the same by reason of the movement of said wheel-carrying frame. This is also a feature of my invention.

My invention provides simple and convenient mechanism for supplying ink and for removing the surplus ink, keeping the type uniformly inked, so that all of the characters are ready to make a proper impression at any time under the control of a finger key.

The present application is a continuation in part of my copending application No. 62,467, filed February 5, 1936 which matured as Patent No. 2,165,223, July 11, 1939.

The invention is hereafter more fully described in connection with the drawings and the essential novel characteristics are summarized in the claims.

In the drawings, Fig. 1 is an end elevation of a printing machine having my inking mechanism; Fig. 2 is a plan of the inking mechanism; Figs. 3 and 4 are vertical sections of the inking mechanism, the planes of the sections being indicated by the correspondingly numbered lines on Fig. 2; Fig. 5 is a front elevation of the type wheel mechanism; Fig. 6 is a diagrammatic perspective of gearing and other parts employed in the operation of the printing mechanism.

Briefly, the embodiment shown comprises a rocking frame 10, carrying a plurality of type wheels mounted side by side, and designated 20 as a unit. These wheels are rigid with each other and any one of them may coact with a narrow

paper carrier 38 under the control of a shift key (not shown) which, through a link 12, may shift the rocking frame axially of the wheels. The rocking frame carries also the inking system in constant engagement with the type wheels. The key board, of which one key is shown at 58, controls the rotation of the type wheels to ink them and bring the desired character into registration with the platen 39, which registration is automatically followed by the swinging of the frame 10 to effect the impression. In the present embodiment of the invention I have illustrated three type wheels 21, 22, 23, each of which is mounted on a shaft 25, which is carried by the rocking frame 10. This frame is swingably mounted on a shaft 40, 15 which is journaled in the main frame 8. As shown, each type wheel carries on its periphery two annular sets of type. The type in the left-hand band or ring of type shown in Fig. 5 may comprise upper case type, whereas the right-hand 20 band of the same wheel includes the lower case type. Of the three type wheels shown; the left-hand type wheel 21 may carry, for instance, eight-point type; the middle wheel, ten-point type, and the right-hand type wheel, twelve-point type. The type wheels may be made of metal, preferably a light metal, such as an aluminum alloy, or of "Bakelite," hard rubber or some other similar non-metallic composition.

I will now describe the inking mechanism with which the present invention is concerned, after which I will explain the mechanism shown for rotating the type wheels to ink them and position them for the selected characters, and the mechanism, operating consequent upon such positioning, for rocking the frame which carries the type wheels and inking mechanism to effect the impression without disturbing the relation of the type wheels to the inking system.

The type wheels 20 are supplied with ink from a suitable ink fountain by suitable rolls, as best illustrated in Figs. 2 and 3. As there shown, the ink fountain is mounted on the type wheel rocking frame 10, and comprises the usual fountain trough 68, in which a fountain roll 61 is intermittently rotated. A ductor roll 62 is mounted on a pair of levers 63, which are pivotally mounted on a shaft 64, journaled in the rocking frame. The ductor roll is alternately brought into engagement with the fountain roll and a reciprocating transfer roll 65, by a cam 67, carried on the periphery of one of the type wheels 20, as indicated in Fig. 1. A suitable spring 68 serves to maintain either the roller in engagement with the

cam, or the ductor roll in engagement with the fountain roll.

The roll 65 is reciprocated to aid in the distribution of ink, in a direction parallel with the axis of the type wheels. This roll is secured to a shaft 69, which is engaged by a forked end of a lever 70, which is pivoted intermediate its ends, as at the rocking frame 10. At its lower end the lever 70 is provided with a roller 71, arranged to engage a cam 75, which is drivingly secured to the shaft 25. The transfer roll 65 transfers the ink from the ductor roll 62 to a form roll 80, carried by a suitable shaft 81, journaled in the rocking frame.

15 Excess ink on the type wheels is removed by a cleaning or scavenging roll 90 of composition or rubber, carried by a shaft 91, journaled in the rocking frame 10. Ink is transferred from this roll to a steel roll 92 carried by a shaft 93, journaled in the rocking frame. The ink is removed from the roll 92 by a pivotally mounted scraper 95 retained in contact therewith by a spring 96. A reservoir 97 may be used to prevent the excess ink from reaching the various parts of the mechanism. The inking mechanism rolls are positively driven by suitable gears secured to the respective roll shafts.

The scavenging operation, which constitutes the main portion of the present invention, is of great value wherever a type wheel is employed which is entirely inked on each revolution, but of which only one character, or an axially extending line of characters, is used for each impression. In such case, the ink application must be sufficiently plentiful so that all of the characters are well inked on a single rotation, so that any of them will be available for printing, from which it results that the unused characters are likely to be overinked. I have found that 35 my scavenging roll acting on the type wheel between the time of imprint and the succeeding inking is very effective, as it removes the surplus ink from the unused characters, so that a relatively uninked type wheel is presented to the inking roller, and thus a uniform inking thereof is effected. Such system has additional importance where several wheels are used, only one of which may be active for a considerable period in the operation of the machine.

50 I have referred to the inking rolls being all driven by suitable gears. More specifically, I have shown the form roll having a gear 101, and the main scavenging roll a gear 102, each meshing with a gear 100 on the type-wheel shaft. 55 The secondary scavenging roll 92 has a gear 103 meshing with the gear 102.

The feature of my invention which relates to the operation of the fountain roll is best shown in Fig. 4. The shaft 110 of this roll has secured to it a ratchet wheel 111. An upright bar 112 is pivotally attached to the frame of the machine at 113, and at its upper end has a slot 114 extending about the shaft 110. The bar 112 carries at its upper end a pawl 115, which is maintained in engagement with the ratchet wheel by a spring 116.

It results, from the mechanism just described, that as the rocking frame 10 is lowered to effect the printing the ratchet wheel moves downwardly and the pawl engages a higher tooth on the wheel; then, as the rocking frame is returned to its uppermost position, the pawl holding the ratchet tooth causes the ratchet wheel to be turned a small amount to feed it ink from beneath the fountain blade which is held against

the fountain roll by adjustable fountain screws 120. This makes a very simple fountain operation and causes the fountain roll to move forwardly consequent upon each impression.

While my invention is independent of the specific construction of the type wheels, and independent of the means by which the type wheels are positioned under the control of the keyboard, nevertheless, for the sake of completeness, I will specifically describe such construction and operation, so far as shown in the drawings hereof, reference being made to my parent application mentioned for a fuller description.

One face of each type wheel is shown as provided with a recess occupied by a pin 24 on the next adjacent type wheel. The pin 24 of the type wheel furthest to the right, (Fig. 5) engages a similar recess in a gear 27, which is mounted on the shaft 25. Thus, when the gear is rotated, the type wheels are rotated in unison therewith. The amount of such rotation is controlled by the key board, as will be hereinafter more fully described.

It will be noted from Fig. 5 that the type wheels may be readily removed without disturbing their driving gear 27, or a type wheel registering gear 28, hereinafter to be more fully described. To this end the gears 27 and 28 are mounted on a sleeve 29, carried by the rocking frame 10, and this sleeve, in turn, rotatively supports the shaft 25. Hence, the shaft 25 may be withdrawn without disturbing the gears.

The type wheels 20 are normally rotating and are brought to a stop with a selected character in the printing position by the operation of the key board. As illustrated, the type wheel driving gear 25 meshes with a gear 141, which has a splined driving connection with the shaft 40, on which the rocking frame 10 is pivotally mounted. A driving belt (not shown) continuously rotates a pulley 142, which is rotatively mounted on the right-hand end of the shaft 40, as illustrated in Fig. 6. The pulley 142 is drivingly connected to the shaft 40 by a normally active slip clutch 143.

As heretofore mentioned, the type wheel, which is above the platen 30, is brought to rest with a selected type in printing position, that is, immediately above the platen bar or at the lowermost point on the type wheels, so that consequent upon the rocking of the frame 10 about the shaft 40, the lowermost type will leave an impression on the work sheet which lies across the platen.

The stopping of the rotation of the type wheels is under direct control of the keyboard. Referring specifically to Fig. 6, the keyboard includes a series of character keys 50. Each character key is supported by an upstanding arm of a lever 151 of a compound key lever. The levers 151 of all key levers are pivoted to a common shaft 152. The normal position of the key levers is shown by the lever in Fig. 6. Here it will be noted that the key lever 151 is provided with a notch 153, which provides a seat for a pin 154, carried by a lever 155, which forms the other member of the compound key lever. The key levers 155 are pivotally mounted on a common shaft 156. The pins 154 are normally maintained in respective notches by springs 157.

The movement of any released lever 155 from the position shown in Fig. 6 stops the type wheel with the character corresponding to the character represented by such key lever, in printing position. This movement of the key lever also releases for action a mechanism which causes the

type wheels to be rocked about their pivot shaft, to cause the selected character to be impressed upon the work. Likewise, this movement also causes the platen and paper carriage to be advanced at a distance equivalent to that required by the selected character, immediately after the impression of such character takes place, thereby positioning the work sheet for the impression of the next succeeding character. These operations are effected as follows:

The rocking of any lever 155 stops the type wheels by the operation of a corresponding stop lever 160. The shaft 40, which drives the type wheels, is provided with a series of discs 161, which are drivingly secured thereto, there being one disc for each key lever mechanism. Each disc 161 is provided with a shoulder 162, and it will be noted from Fig. 6 that these shoulders hold a different angular position relative to the axis of the shaft 40, such positions being equal to the angular positions of the type about the periphery of the type wheels. Each shoulder 162 is arranged to be engaged by an abutment 163 of its respective stop lever 160. The latter levers are pivoted on a ball 165, which is, in turn, pivoted to the frame at 166.

The stops 163 are normally held out of the path of the shoulders of their respective discs 161 by the key lever members 155, heretofore described. When, however, a key is depressed, the corresponding lever 155 is rocked in clockwise direction by its respective spring 157 and causes a spring 168, interconnecting such lever and its respective stop lever 160, to raise the stop shoulder 163 into contact with the path of the shoulder 162 of its respective disc 161. Hence, the rotation of the shaft 40 will be stopped when the shoulder 162 of such disc engages the abutment of the corresponding stop lever 160. The friction clutch 143, heretofore described, permits the stopping of the shaft 40 without interference with the operation of the power mechanism or damage to the parts. This stopping of rotation of the shaft 40 stops the type wheel with the selected character in printing position, which character is represented by the key 50, which was depressed.

When a disc 161 engages a stop lever 160, it moves it forward, thereby rocking the ball 165 about its pivot 166, against the action of a spring 167 interposed between the ball and a stationary frame member. The movement of this ball rocks a lever 170 about its pivot 171, withdrawing the right-hand end of said lever (Fig. 6) from the path of a latch 172, of a clutch member 173. This clutch member is drivingly secured to a gear 175 and both the member and the gear are rotatively mounted on a shaft 176. The gear 175 meshes with a gear 178, which is drivingly connected to the driving pulley 142. This clutch is of the usual single revolution type, and when the shaft has made one complete revolution, the latch 172 will be cammed out of engagement by the lever 170, which, at that time, will have been returned to its normal position.

The shaft 176, during the first-half of its revolution, acts to rock the type wheels to cause an impression to be made upon the work sheet. As shown in Fig. 6, an eccentric bushing 180 is secured on the end of the shaft 176, and through a connecting rod 181, the upper end of which is pivoted to the rocking frame 10, which causes such frame to be rocked about its pivot shaft 40, thus causing an impression to be made.

75 The rocking of the frame 10 to make an im-

pression accurately, positions the type which has been moved substantially to the printing position by the key lever mechanism. As illustrated in Fig. 4, an indexing gear 28, which rotates as a unit with the type wheels, engages a precision dog 185 as the carriage is swung downwardly about its pivot. This engagement takes place before the type strikes the work and is effective to accurately index the type wheels.

During the last half of the movement or rotation of the shaft 176, the type wheel is retracted from the work, the paper carriage and platen are advanced into position for the impression of the next character by mechanism not shown, and the key lever mechanism is reset to prepare the keyboard for the impression of the next key by the operator. The resetting of the lever mechanism is accomplished by an enlarged eccentric portion 188 of the shaft 176, which overlies the key levers 155. Consequent upon the rotation of this eccentric portion of the shaft, these levers are rocked counter-clockwise about their pivots 156, thus withdrawing the stop-shoulder 163 from its corresponding disc 161 and re-engaging the pin 154 in the notch of the key lever 155. At the same time the spring 167 restores the lever 170, thereby causing the rotation of the shaft 176 to cease, following the completion of one revolution.

I claim:

1. In a printing machine, the combination of a 30 rocking frame, a type wheel and an inking mechanism therefor, both carried by the frame, said inking mechanism having a fountain roll, a platen toward and from which the type wheel may be rocked and mechanism to give the fountain roll 35 periodic rotations consequent upon the rocking of the frame toward the platen and its return movement.

2. In a printing machine, the combination of a 40 rocking frame, a printing wheel mounted therein, an inking system carried by the rocking frame having a fountain roller and a form roll to feed ink to the printing wheel, a ratchet wheel on the fountain roll, and a pawl carried independently of the rocking frame and coacting 45 with the ratchet wheel, whereby the rocking movement of the frame automatically turns the fountain roll.

3. In a printing machine, the combination with 50 a stationary frame of the machine, of a rocking frame mounted thereon, a type wheel and an inking system both mounted on the rocking frame, said inking system including a form roll engaging the type wheel, and a fountain roll to supply ink for the form roll, said fountain roll having 55 a shaft with a ratchet wheel rotatable therewith, a link pivoted to the main frame and slotted about the shaft of the fountain roll, and a pawl carried by the link and coacting ratchet wheel.

4. In a printing machine, a main frame, a 60 type wheel, a carriage pivotally mounted on the frame and adapted to rotatably support the type wheel, means to continuously drive the type wheel, means to stop the type wheel with a selected type in printing position, means to rock the carriage 65 about its pivot to cause an impression to be made from such selected type, an inking mechanism for said type wheel including an ink fountain and a fountain roll carried by said carriage, means to transfer ink from the inking mechanism to the 70 type wheel, means to intermittently move the fountain roll about its axis consequent upon the rocking of the carriage about its pivot.

5. In a printing machine, the combination of 75 a frame, a plurality of rotary type carrying wheels

mounted in said frame, a platen, means for shifting the frame axially of the wheels as a set with reference to the platen, means for causing coaction between the platen and a type on one of said 5 wheels, an inking system mounted in the frame and including an inking roller coating with the entire set of wheels to supply ink thereto, a

scavenging roller mounted in the frame and co-
acting with the entire set of wheels to remove sur-
plus ink therefrom, and means mounted in the
frame for removing surplus ink from the scaveng-
ing roller.

CLIFTON CHISHOLM.
